[57] **CLAIM**

The ornamental design for a sofa, as shown and described.

DESCRIPTION

FIG. 1 is a perspective view of a sofa showing my new design;

FIG. 2 is a front elevation view thereof;

FIG. 3 is a right side view thereof, the opposite side being a mirror image of the side shown;

FIG. 4 is a top plan view thereof; and,

FIG. 5 is a rear elevation view thereof.

FIGS. 2 through 5 have been shown on a reduced scale with respect to FIG. 1.
